DESIGN FOR A TRUCK FOR A TRAVELING CRANE

Robert J. Stoddard, St. Paul, Minn., assignor to
American Hoist and Derrick Company, St. Paul,
Minn., a corporation of Delaware

Application November 21, 1941, Serial No. 104,239

Term of patent 14 years

To all whom it may concern:

Be it known that I, Robert J. Stoddard, a citizen of the United States, residing at St. Paul, in the county of Ramsey and State of Minnesota, have invented a new, original, and ornamental Design for a Truck for a Traveling Crane, of which the following is a specification, reference being had to the accompanying drawing, forming part thereof.

Fig. 1 is a side elevational view of a truck for a traveling crane showing my new design;

Fig. 2 is a top plan view;
Fig. 3 is a front elevational view; and
Fig. 4 is a rearward elevational view.

The opposite side of the device is substantially the same as shown in Fig. 1.

I claim:

The ornamental design for a truck for a traveling crane, as shown and described.

ROBERT J. STODDARD.
